BAND HEATER RELEASE

Anton Van Veen, Brooklyn, N. Y., assignor to
 American Machine & Foundry Company, a corporation of New Jersey

Application March 15, 1934, Serial No. 715,726

5 Claims. (Cl. 154—1)

This invention relates to wrapper banders for wrapping machines wherein a label band is attached to the main wrapper web by application of heat, its main object being to provide means for automatically withdrawing the label band from contact with the heater, thus preventing the band from being overheated while the feed of the wrapper web is interrupted.

This is accomplished by threading the label band through a rack back of the heater, and from there onto the main wrapper web in such a manner as to be swung clear of the heater when the main wrapper drive stops. Whenever the wrapper reel stops, the band reel, due to its 15 inertia, delivers an amount of slack and, since the rack is pivoted above the heater and counterbalanced sufficiently to recover some of the slack between the rack and the band reel, it swings away from the heater, carrying with it the label band and holding that position until the main 20 wrapper drive starts.

The band rack can be made sufficiently wide to accommodate a very wide band or two or more narrow bands arranged to run side by side.

25 In the accompanying drawing which shows the application of this invention to the bander attachment of a bread wrapping machine operating to wrap the loaves in waxed paper or similar materials,

30 Fig. 1 is a sectional elevation showing how the label band is threaded through the release rack and onto the main wrapper web;

Fig. 2 is a cross-section on line 2—2 of Fig. 1; Fig. 3 is an end elevation of Fig. 1; and

35 Fig. 4 is a view showing a finished package having a band wrapper.

In carrying the invention into effect there is provided a heater unit, means for intermittently feeding a continuous band over said heater unit in contact therewith, and mechanism for automatically moving the band out of contact with said heater unit when its feed is interrupted. In the best constructions contemplated, said mechanism includes a pivoted rack adjacent said heater 40 unit, spaced bars on said rack adapted to guide the band into position to be pressed against said heater unit by the feeding tension applied to the band, and counter-weights on said rack for swinging it away from said heater unit with the band whenever the feeding tension is removed from the band. These various means and parts 45 may be widely varied in construction for the particular device selected to illustrate the invention is but one of many possible concrete embodiments 50 of the same. The invention, therefore, is not to 55

be restricted to the specific construction shown and described.

Referring to the drawing, Figs. 1 and 3, the band reel BR on shaft 12 is shown suspended from rods 13 and 14 of the machine by hangers 15 and 16. The heater unit 17, Figs. 1 and 2, is shown mounted in arms 18 and 19 fast to shaft 20, which is journaled in hangers 21 and 22 suspended from rods 13 and 14. The heater unit 17 consists of a flanged roller loosely mounted 10 on a cartridge type electric heater carried by arms 18 and 19 and connected to an electrical supply circuit by wires passing through switch box SB, located at a convenient point on the machine. The material used for the label band 15 may be waxed paper, or any other suitable material.

Shaft 20 by means of crank 23 can be turned by shifting crank latch 23a from its position in hole 22a to hole 22b on quadrant 22c. By this 20 means the heater unit and the parts comprising the release mechanism may be swung out of the way for convenience in replacing a depleted wrapping material roll by a new roll.

The web feed for the wrapping material W, as 25 well as the loaf feed and wrapping mechanism, may be similar to those disclosed in Patent No. 1,926,245, granted Sept. 12, 1933, on the application of F. R. Schmitt, but with the heater unit 17 for the label band located behind the roll of 30 wrapping material W, thus heat sealing the band B to the wrapping material W immediately as they contact on the roll WR.

The label band B is threaded over and in front of shaft 20 and hinge rod 25, Fig. 1, then to the 35 rear of bars 26 and 27 in rack 28 and between the flanges of the heated roller onto the wrapping material roll WR, where the heated band adheres to the web W and is carried along with it over the various rollers into the wrapping machine. 40

Rack 28 is pivoted on hinge rod 25 and is counter-balanced by adjustable weights 29 so as to assume a position, as indicated by dotted lines at 28' in Fig. 1, when the rotation of roll WR has stopped, to take up the slack B' established 45 in band B between shaft 20 and band reel BR by the over-travel of reel BR, due to its inertia.

As long as the web W is being uncoiled from roll WR the band B is held in contact with heater 50 17, but if roll WR stops, the rack 28 is swung 50 into the dotted position 28' and the bars 26 and 27 thereof take up the slack B' between shaft 20 and band reel BR and, in so doing, pull band B out of contact with heater 17. The object of this invention is thus automatically accomplished 55

and obviates the necessity for any manual operation to prevent overheating of the wrapper band.

What is claimed is:

1. The combination with a heater unit, of means for intermittently feeding a continuous band over said heater unit in contact therewith, and mechanism for automatically moving the band out of contact with said heater unit when its feed is interrupted.
2. The combination with a heater unit, of means for intermittently feeding a continuous band over said heater unit in contact therewith, and mechanism for automatically moving the band out of contact with said heater unit when its feed is interrupted, said mechanism including a pivoted rack adjacent said heater unit, spaced bars on said rack adapted to guide the band into position to be pressed against said heater unit by the feeding tension applied to the band, and counter-weights on said rack for swinging it away from said heater unit with the band whenever the feeding tension is removed from the band.
3. The combination with a sealer unit, of means for feeding a continuous band over said sealer unit into contact therewith, automatic mechanism for relatively moving said band and sealer unit to separate them when the feed tension on the band is interrupted, mechanism for supporting a reel of wrapping material, band guiding means holding a portion of the band after the same has been acted upon by said sealer unit in contact with a portion of the wrapping material

on the reel to seal the band to said material, and devices for guiding the united band and wrapping material from the reel toward a wrapping position.

4. The combination with a sealer unit for rendering said band adhesive, of means for feeding under tension a continuous band over said unit in contact therewith, and mechanism for automatically moving the band out of contact with said sealer unit when said tension is relieved, said mechanism including an element contacting the band adjacent said unit, and devices yieldingly supporting said element to urge the band out of contact with the sealing unit with a force insufficient to overcome feeding tension of the band whereby when the band is under tension it contacts the sealing unit against the action of said devices and when the tension is released the band is automatically moved out of contact with the sealing unit.

5. The combination with a heat sealing unit, of means for intermittently feeding a continuous band of heat sealable material over said sealer unit into contact therewith, mechanism for supporting a reel of wrapping material, band guiding means acting on a heated portion of the band to hold the same in contact with the wrapping material while the material is still on the reel to unite the band with the material, and devices for guiding the united band and material from the reel.

ANTON VAN VEEN.
